LLP

(57) **CLAIM**

The ornamental design for a handle, as shown and described.

DESCRIPTION

FIG. 1 is a perspective view of a handle of the new design;
FIG. 2 is a front elevational view of the handle of FIG. 1;
FIG. 3 is a rear elevational view of the handle of FIG. 1;
FIG. 4 is a left side elevational view of the handle of FIG. 1;
FIG. 5 is a right side elevational view of the handle of FIG. 1;
FIG. 6 is a top plan view of the handle of FIG. 1; and,
FIG. 7 is a bottom plan view of the handle of FIG. 1.

The portions of the Figures shown in broken lines are not part
of the claimed design and are for illustration only.

1 Claim, 3 Drawing Sheets
